UNITED STATES PATENT OFFICE.

WILLIAM R. COCHRAN, JR., OF TOLEDO, OHIO.

FUEL-OIL BURNER.

1,107,900.

Specification of Letters Patent. Patented Aug. 18, 1914.

Application filed November 5, 1913. Serial No. 799,344.

To all whom it may concern:

Be it known that I, WILLIAM R. COCHRAN, Jr., a citizen of the United States, and resident of Toledo, in the county of Lucas and State of Ohio, have invented certain new and useful improvements in Fuel-Oil Burners; and I do hereby declare the following to be a full, clear, and exact description of the invention, such as will enable others skilled in the art to which it appertains to make and use the same.

My invention relates to an improvement in fuel oil burners, the object being to provide an oil burner that will be simple, economical and be easily and readily applied within the fire pot of any ordinary coal or wood burning stove, and it consists in the parts and combination of parts as will be more fully described and pointed out in the claims:

In the accompanying drawings, Figure 1 is a view in perspective of my improved device; Fig. 2 is a view in longitudinal section through the fire pot of a stove and through the hollow frame of the burner; Fig. 3 is a view in transverse vertical section on the line $x-x$ of Fig. 2, and Fig. 4 is a similar view on the line $y-y$.

1 represents a supporting frame of such size as to be readily entered in the fire pot 1^a of an ordinary coal or wood burning stove. This frame is hollow and is preferably made of cast metal, rectangular in shape, closed at one end and open at the other end, and is provided in its top with a flanged opening or openings 2 for the passage upwardly of air to the burner orifices. The portions of the top of the frame at opposite sides of the openings 2, are inclined upwardly toward said openings, and the latter are located at the top of the incline 3, the underside of the latter surfaces forming deflectors which deflect the air to the exit openings 2. This frame 1 is divided longitudinally by a centrally located horizontal partition 1^b extending from a point adjacent the front open end of the frame to a point in rear of the front air exit 2, and then projects upwardly to the top plate of the frame, forming a flue 4 through which air passes to the front air exit and burner ori-

fices over same, while the portion of the frame below and to the rear of partition 1^b, forms the supply flue 5 for the rear air opening 2.

The front open end of the frame 1 is adapted to pass through a door opening at the end or side of the stove, as shown in Fig. 2, and said open end may project more or less according to the size of the fire pot. This permits the burner to be so located within the fire pot, as to bring the burner orifices properly under the openings in the top of the stove.

The gas generating and burning structure 65 comprises three connected parallel pipes, one of which 7 is connected with the oil supply pipe 8. This pipe 8 is connected with a source of oil supply preferably located so that the oil will be supplied to pipe 70 by gravity. Pipe 7 to which pipe 8 is connected, is located in a vertical plane to one side of the burner orifices, but is within the heating zone of the latter, so that the oil passing therethrough will be highly heated, and it is preferably filled with wire strands extending lengthwise the pipe and loosely filling the same so that the comparatively small quantity of oil therein will be impeded in its progress through the pipe. 80 This pipe 7 is connected by an elbow 18 with the vaporizing pipe 9, which is connected with the burner pipe 10. Pipe 10 is substantially parallel with the pipes 7 and 9, and is located immediately under pipe 9 85 so that the latter will be directly exposed to the heat from the burner orifices. The pipe 9 in which the heated oil is vaporized, or in which any vapor generated in pipe 7 is superheated, may also be loosely filled with wire which will impede the progress of any oil through the pipe and increase the heating surface to which the oil and vapor is subjected.

The burner pipe 10 is made of brass and is of smaller diameter than either pipe 7 or 9 so that the pressure of the vapor will be increased in the burner, and it is provided with a burner orifice 11 for each air opening in the frame 1. These burner orifices are quite minute, and are located centrally over the air openings 2 in the frame 1, so that the

air passing up and around the burner pipe will be about evenly divided at the two sides of the latter.

With burner pipes made of iron or steel, 5 the intense heat corrodes the pipe and causes it to scale. By making it of brass all corroding and scaling is avoided and consequently there is no clogging of the burner openings due to such corroding and scaling.

10 The frame 1 is provided on its top with two starting cups 12 and 13, which latter are simply depressions in the top plate, and are adapted to receive oil, or asbestos pads soaked with oil, which when ignited, will 15 heat the pipes 7—9 and 10 sufficiently to start the vaporization in pipes 9 and 10. This frame is also provided at its rear end with an upwardly projecting integral flange 14, provided on its inner face with two vertical parallel ribs 15 and 16, separated sufficiently to receive between them the closed free end 17^a of the burner pipe 19, and the rib 16 is provided with a hook shaped upper end 17, adapted to take under the elbow 25 18 and support and sustain the rear ends of the pipes in proper position relative to the air openings in the frame 1. The frame 1 is also provided in advance of the oil cup 12, with a flange 19 having a slot for the passage of the end of the pipe 8, so as to prevent any lateral displacement of the burner pipes at the front. The pipe 10 preferably rests in grooves 20 formed in the raised portion 30 of the top of the frame adjacent the air openings in the latter.

With this construction the gas generating and burning structure as a unit, can be lifted from frame 1, and when seated on the latter, will be held securely against the possibility 10 of accidental displacement.

The open end 6 of the frame 1, is smaller than the door opening in the stove and to cover said opening I use a plate 21 having an opening therein of a size to receive said 45 end 6, so that when said plate is moved up against the outer side of the door opening in the stove it will close the latter, to all air except that entering through the frame. The end 6 of the frame is adapted to project 50 through the door, so that it takes the air direct from the outside of the stove, consequently this plate will be used only in instances where the end 6 does not substantially fill the door opening.

55 In order to further support the pipe system I cast the post 22 integral with top of frame 1, about midway the burner orifices 11, and in a position to engage and form a seat for pipe 7 and I provide the said post 60 22, with a lateral extension 23, curved on its upper face as shown in Fig. 3, concentric with the curvature of pipe 9, and but slightly removed from the latter. This curved extension 23 forms a support for the 65 bar 25 connecting the two flame spreaders

26. These flame spreaders are simply disks of metal which spread the flame into circular form and also assist by the heat they absorb, in vaporizing the oil in the pipe 9. Each spreader is provided on its upper side 70 with a curved seat to engage the underside of the pipe 9, and they are both retained against said pipe by the curved face of the extension 23. The bar however is free to be moved to remove, replace or properly adjust 75 the spreaders with relation to the burner orifices, so as to permit the said spreaders to be so placed centrally with relation to the flame.

Having fully described my invention what 80 I claim as new and desire to secure by Letters-Patent, is:—

1. The combination of a hollow frame closed at one end and open at the other end and provided with a plurality of air openings and with a partition forming flues, one flue leading to one air opening and the other flue to the other air opening, means integral 85 with the top of the frame for supporting a gas generating and burning structure, and 90 a gas generating and burning structure detachably mounted on said frame.

2. The combination of a hollow frame open at one end and provided with an air exit in its top, and with flanges at opposite 95 sides of said opening, one of said flanges having parallel ribs between which the free end of the burner pipe rests, and one of said ribs constructed to support the fuel pipe, the other flange having a slot for the passage of one of said pipes, and a gas generating and burning structure composed of a plurality of pipes one of which is the burner pipe, the said gas generating and burning structure being detachably supported on 105 said frame with its burner orifice over the air opening in the frame.

3. The combination of a hollow frame closed at one end and open at the other, and provided in its top with an air exit, and on 110 its top with means for detachably supporting a burner pipe, a gas generating and burning structure composed of a plurality of pipes one of which is the burner pipe and another the fuel pipe, the said structure being detachably supported as a unit on said frame, and a flame spreader detachably and adjustably supported against the underside of said fuel pipe and in a plane above said burner pipe.

4. The combination with a hollow frame provided with a plurality of air exit openings in its top, a post fixed to the top of said frame and provided with a concaved seat, and a gas generating and burning structure comprising a liquid fuel pipe and a burner pipe and a plurality of connected flame spreaders, the connection between said spreaders resting on said concave seat and holding the spreaders against the fuel pipe 120 125 130

and over the burner openings in the burner pipe.

5. The combination of a gas generating and burning structure composed of a plurality of pipes one of which is a burner pipe and another a fuel pipe, a plurality of integral connected flame spreaders, and means independent of said pipes and also of said spreaders and their connection, and engaging the latter intermediate the spreaders for

adjustably holding said connected spreaders adjacent the fuel pipe and over the burner orifices in the burner pipe.

In testimony whereof, I have signed this specification in the presence of two subscribing witnesses.
